UNITED STATES PATENT OFFICE.

FELIX BROWN, OF NEW YORK, N. Y.

FOG-SIGNAL.

SPECIFICATION forming part of Letters Patent No. 236,772, dated January 18, 1881.

Application filed December 15, 1880. (No model.)

To all whom it may concern:

Be it known that I, FELIX BROWN, a citizen of the United States, residing at New York, in the county and State of New York, have invented new and useful Improvements 5 in Fog-Signals, of which the following is a specification.

This invention relates to an improvement in that class of fog-signals which are known as 10 "sirens."

My invention consists in the combination, in a siren, of a suitable casing with one or more openings for admitting air, and two or more openings for discharging the air, and a 15 fan-wheel which revolves in the casing and serves to draw in the air through one set of openings, and to discharge it in intermittent currents through the other set of openings; also, in the combination, in a siren, of a cylindrical casing with openings in its periphery and in one of its heads, a fan-wheel mounted 20 on a shaft and adapted to revolve in the interior of the casing, openings in the jacket of the fan-wheel which can be made to register with the openings in the casing, and wings on said 25 fan-wheel constructed to draw in air through one set of openings in the casing and to drive it out intermittently through the other set of openings; also, in the combination, with the 30 casing and the fan-wheel constructed as above described, of mechanism for adjusting the fan-wheel in relation to the air-escape openings.

This invention is illustrated in the accompanying drawings, in which Figure 1 represents a vertical section in the plane $x-x$, Fig. 35 2. Fig. 2 is a front view. Fig. 3 is a horizontal section in the plane $y-y$, Fig. 2. Fig. 4 is a detached sectional view of the fan-wheel on a larger scale than the previous figure.

Similar letters indicate corresponding parts. 40 In the example shown in the drawings, the letter A designates a cylindrical casing, which is provided with a series of openings, a , in its periphery, and with openings b in its head 45 B. Through this casing extends a shaft, C, which has its bearings at one end in the head B, and at its opposite end in a standard, D, secured to the casing A. On this shaft is mounted a fan-wheel, E, which is 50 composed of a solid disk, c , a cylindrical jacket, d , a series of radiating wings, e , and

a ring, which is connected to the disk c by the jacket d and the wings e . In the jacket d are a series of openings, f , Fig. 4, by preference just in front of the radiating wings e , and said jacket is of such a diameter that it fits into the casing A, and can be revolved therein. 5

The shaft C of the fan-wheel is mounted in its bearings in such a manner that it can be moved therein in the direction of its length, 60 and if the fan-wheel is brought in such a position that it covers the openings a in the casing A, either partially or wholly, and a revolving motion is imparted to it, the air, which is drawn in through the openings b in the head 65 B, is expelled through the openings f in the jacket d of the fan-wheel and through the openings a in the periphery of the casing A. As the openings f move past the openings a the latter openings are alternately opened and 70 closed, and the currents of air discharged through them are intermittent—or, in other words, a rapid vibration is imparted to the air as the same enters the openings b and as it escapes from the openings a , and a loud tone 75 is produced. The volume of the tone and its pitch depend chiefly upon the velocity with which the fan-wheel is revolved; but if the fan-wheel is revolved with uniform velocity the volume of the tone can be changed by 80 moving the fan-wheel shaft in its bearings so as to uncover the openings f , more or less. By moving the shaft so as to uncover these openings gradually, while the fan-wheel is in motion, the tone is swelled, and vice versa, and by 85 these means a peculiar effect can be produced with my siren, so that its tone can be heard at a great distance and readily distinguished from other tones.

In order to increase the volume of the tone 90 the casing A is surrounded by a conical jacket, F, which also forms a portion of the frame G, that supports the driving mechanism. This mechanism consists of a pulley, H, mounted on the fan-wheel shaft, a counter-shaft, I, 95 mounted in the frame G and carrying a pinion, J, and a pulley, K, and a driving-shaft, L, mounted in the frame G and carrying a cog-wheel, M, and a hand-crank, N. The pulleys K and H are connected by a belt, and the cog-wheel M gears into the pinion J, and the diameters of these wheels and pulleys are so se- 100

lected that one revolution of the driving-shaft produces a large number of revolutions of the fan-wheel, and that with comparatively little exertion a very rapid motion can be imparted 5 to said fan-wheel.

On the frame G is also mounted a vertical shaft, O, which carries at its upper end a hand-lever, P, and at its lower end a pinion or toothed segment, Q, Fig. 3, which gears into 10 circular grooves *i* in the fan-wheel shaft. A spring, *j*, which acts on the shaft O, has a tendency to retain the same in such a position that the openings *f* in the jacket of the fan-wheel are wholly covered by the solid portion 15 of the casing, and do not register with any portion of the openings *a* in the casing. When a revolving motion is imparted to the fan-wheel, and the vertical shaft O is turned gradually against the action of its spring *j*, the 20 openings *f* are gradually uncovered and brought to register with the openings *a*, and a tone of gradually-increasing volume is produced. By allowing the shaft O to follow the 25 action of its spring the volume of the tone is gradually reduced, and when the openings *f* in the fan-wheel come opposite the solid portion of the casing no tone is produced.

This siren is intended particularly as a fog-signal for sailing-vessels, and it is therefore so arranged that it can be operated by hand; but it may be driven by any other power, or by steam if it is to be used on a steam-vessel. It must also be remarked that the principal 30 advantage of my siren is due to the fact that it supplies its own air, while sirens heretofore constructed were dependent upon currents of compressed air or steam, which had to be supplied by proper mechanical means.

The action of my siren depends chiefly upon 35 the fan-wheel, which draws in air through one set of openings, and expels the air in intermittent currents through another set of openings.

The shaft O may also be operated automatically in such a manner that the openings *f* are

covered and uncovered at certain intervals, thus producing a series of penetrating sounds of longer or shorter duration, according to a prearranged signal.

With the jacket F may be connected a trumpet or horn, should circumstances require it. 50

My siren can be built on any scale, and it will also be a very efficient fog-signal for lighthouses and light-vessels.

What I claim as new, and desire to secure 55 by Letters Patent, is—

1. The combination, in a siren, of a suitable casing with one or more openings for admitting air, and two or more openings for discharging the air, and a fan-wheel which revolves in the casing and serves to draw in the air through one set of openings in the casing, and to discharge it in intermittent currents through the other set of openings, substantially as described. 60

2. The combination, in a siren, of a cylindrical casing with openings in its periphery and in one of its heads, a fan-wheel mounted on a shaft and adapted to revolve in the interior of the casing, openings in the jacket of the fan-wheel, which can be made to register with the openings in the casing, and wings on said fan-wheel, constructed to draw in air through one set of openings in the casing and drive it out intermittently through the other 70 set of openings, substantially as set forth. 75

3. The combination, with the casing A and its two sets of openings, of a fan-wheel constructed to revolve in the casing, and of mechanism for adjusting the fan-wheel in relation to the air-escape openings, substantially as herein shown and described. 80

In testimony whereof I have hereunto set my hand and seal in the presence of two subscribing witnesses.

FELIX BROWN. [L. S.]
